UNITED STATES PATENT OFFICE.

AUGUST WITZEL, OF DEADWOOD, DAKOTA TERRITORY.

SUPPORT FOR BUGGY-TOPS.

SPECIFICATION forming part of Letters Patent No. 311,703, dated February 3, 1885.

Application filed August 1, 1884. (No model.)

To all whom it may concern:

Be it known that I, AUGUST WITZEL, of Deadwood, in the county of Lawrence and Territory of Dakota, have invented a new and Improved Support and Buffer for Buggy-Tops, of which the following is a full, clear, and exact description.

The object of my invention is to prevent the breaking of the back bows of buggy-tops as the tops are let down, and also to avoid excessive jumping or shaking of the let-down top and overstraining of its joints and parts when the vehicle is traveling over rough roads.

The invention consists in the peculiar construction and arrangement of parts, as hereinafter fully described, and pointed out in the claim.

Reference is to be had to the accompanying drawings, forming part of this specification, in which similar letters of reference indicate corresponding parts in all the figures.

Figure 1 shows my invention as applied to a buggy-top, and with the top raised. Fig. 2 is a side view showing the top lowered and resting on the buffer-support, and Fig. 3 a sectional plan view showing the joint of the support and buffer with the shifting-rail.

The letter A indicates the improved top support and buffer, which consist of an arm 30 made in two sections, *a* *b*, jointed together on a strong pin at *c*, and a rubber or other suitable cushion or buffer, B, which I prefer to hold to the outer end of the arm A, between side flanges, *d* *d*, of the arm, as shown; but the buffer B may be held to the arm in any ap-

proved way. I attach the arm A to the buggy by placing its section *a* upon the square or angular portion *e* of the stud or pin E, which is fixed to the shifting-rail F, held in any ap- 40 proved way to the buggy-seat, and so that the arm-section *a* will be held against turning on the stud E. I propose to place one at each side of the eye of the arm-section *a* on the stud E, the elastic or other suitable washers, G G, and outside of them on the round portion *e'* of the stud I will place the washer H, outside of which the end *i* of the top prop bar, I, is held loosely, so as to turn on the stud as the buggy-top is raised or lowered. A nut, *f*, on the stud E outside of the bar I, holds it on the stud. It will, however, be understood that the washers G G may be

dispensed with; but in applying my improvement to old buggies I prefer to use them to fill out the space on the square portion *e* of the stud E, which usually is taken up by an elastic buffer placed on the stud and on which the back bow, J, of the buggy-top falls, and in fitting the arm-section *a* on the stud E the same elastic buffer which formerly was on the stud may be used to make the washers G G placed on the stud with the arm-section *a* of my improved top support and buffer, as will readily be understood. I prefer to connect the arm A at its outer end by a link, K, to the top prop bar, I, so that when the buggy-top is raised the arm-section *a* will be raised with and held by the bar I, as in Fig. 1, and so that when the buggy-top is lowered the arm-section *a* will be lowered with it, when the shoulders of the arm-joint at *c* will meet and hold the arm-section *a* rigidly in horizontal position, or nearly so, and so that the back bow, J, of the buggy-top will fall upon the buffer or cushion B at the end of the arm, the link K folding down with the prop-bar I, as shown in Fig. 2. It will be seen that in my improvement the point of support for the back bow of the buggy-top is removed from the shifting-rail stud E and carried back nearly 80 to the outer end or portion of the back bow, and about twice the distance from the main pivot L of the buggy-top, whereby a much more substantial support is given to the top as it falls and afterward, so that in riding over 85 rough roads with the top down the entire top will not be jolted and shaken as when supported at the stud E, and thereby the comfort of riding will be increased and greater durability of the buggy-top insured.

As above intimated, the link K need not be used, as the arm-section *b* may be folded forward on its joint *c* to rest on the buggy-seat when the top is up, and may be thrown back by hand to the position shown in Fig. 2 when 95 the top is to be let down; but by attaching the arm-section *a* by the link K to the prop-bar I, the top-support and buffer A B need no attention from the occupant of the buggy, as they are lowered automatically with the 100 buggy-top and in proper position to receive the back bow on the elastic buffer B of the support.

Having thus described my invention, what

I claim as new, and desire to secure by Letters Patent, is—

A support and buffer for buggy-tops, made with an arm, A, consisting of two sections, *a* 5 *b*, hinged to each other by a stop-joint at *c*, and carrying an elastic block or cushion, B, at its outer end, and said arm-section *a* being fitted on the shifting-rail stud E, so as to be held against turning thereon, in combination

with the top prop-bar, I, pivoted on the stud 10 E, and connected to the head of the arm-section *b* by the link K, substantially as shown and described.

AUGUST WITZEL.
